UNITED STATES PATENT OFFICE.

ROBERT L. INGERSOLL AND THOMAS J. DOUROS, OF BOONE, IOWA.

BLOW-OFF COCK FOR BOILERS.

1,146,797.

Specification of Letters Patent. Patented July 20, 1915.

Application filed February 26, 1915. Serial No. 10,810.

To all whom it may concern:

Be it known that we, ROBERT L. INGERSOLL and THOMAS J. DOUROS, citizens of the United States of America, and residents of Boone, Boone county, Iowa, have invented a new and useful Blow-Off Cock for Boilers, of which the following is a specification.

The object of this invention is to provide an improved construction for blow-off cocks 10 for engine boilers and the like.

A further object of this invention is to provide an improved construction to facilitate removal of sediment from boilers and to accomplish this quickly and thoroughly.

15 A further object of this invention is to provide an efficient blow-off cock and to prevent leakage therefrom during operation.

Our invention consists in the construction, arrangement and combination of elements hereinafter set forth, pointed out in 20 our claims and illustrated in the accompanying drawing, in which—

Figure 1 is a longitudinal sectional elevation of the device. Fig. 2 is a cross-section 25 on the line 2—2 of Fig. 1, dotted lines indicating altered position of some of the parts. Figs. 3 and 4 are cross-sections on the line 3—4 of Fig. 1, showing the device in closed and open position, respectively.

30 In the construction of the device as shown the numeral 10 designates a base member of generally tubular form and open at both ends. The base member 10 is exteriorly threaded intermediate of its ends and is

35 screwed into a threaded opening at the desired place in a boiler, a portion of which is shown and designated by the numeral 11. The connection of the base member 10 to the boiler plate 11 preferably is by a tapered 40 thread, to insure a tight fit and prevent leakage. The base member 10 is interiorly threaded at its inner end and a shell 12 is

45 screwed therein and closes the inner end of said base member. The shell 12 is hollow, is open at its inner end and closed at its outer end, which outer end is formed with an angular projection 13 by means of which said shell is screwed into place. The base member 10 is exteriorly threaded at its outer

50 end and a casing member 14 of tubular form and open at both ends is screwed thereon. The casing 14 is formed with an internal flange or shoulder 15 near its inner end, and packing such as 16 preferably is mounted 55 between said flange and the outer end of the base member 10. A tubular valve member

17 is mounted in the casing 14 and base member 10 and projects slightly from said casing at its outer end. The inner wall of the inner end of the base member 10, and the outer wall of the inner end of the shell 12 are oppositely tapered to form a tapering annular recess therebetween, and the inner end of the tubular valve 17 has its walls tapering to fit snugly within said recess. A 60 cap member 18 is screwed on the exteriorly threaded outer end of the casing 14 over the projecting end of the tubular valve 17. The cap 18 is formed with an internal shoulder 19 adjacent its inner end, and packing such as 20 is mounted between said shoulder and the outer end of the casing 14. An expansive spring 21 is coiled around the outer end portion of the tubular valve 17 and impinges at one end the shoulder 19 and at its 65 opposite end a peripheral flange 22 on said tubular valve. It is the function of the spring 21 to hold the tubular valve 17 snugly to its seat between the members 10 and 12. 70

The inner end of the base member 10 is formed with apertures 23, and the shell 12 is formed with apertures 24 in alinement with said apertures 23. The inner end of the tubular valve 17 is formed with apertures 25 adapted to register at times with the apertures 23, 24, as shown in Fig. 4, and to be moved out of register therewith at times, by rotation of said valve member, as shown in Fig. 3. 80

The casing 14 is formed with a transverse slot 26 intermediate of its ends, and a closing band or ring 27 is rotatively mounted on said casing and closes said slot. An operating handle 28 is mounted snugly through the closing ring 27 and loosely through the slot 26, and is screwed at its inner end into the tubular valve 17. The operating handle 28 projects radially outwardly and is formed with a hole 29 in its outer end to receive connection of an operating rod (not shown) or other device leading to reach of the operator. 95

A nipple 30 is screwed in the interiorly threaded outer end of the cap 18 and is 100 adapted to receive connection of a pipe such as 31 leading to suitable place of discharge.

In practical operation, the valve member 17 normally is kept turned in the position shown in Fig. 3, or in closed position. When 110 it is desired to remove sediment or dirty water from the boiler the handle 28 is turned

to rotate the tubular valve 17 to the end of bringing the apertures 25 into register with the apertures 23 and 24. The sediment or sediment-laden water enters the apertures 23, passes through the apertures 25 and 24 to the interior of the shell 12, and then passes to the tubular valve 17 and through the nipple 30 to the pipe 31, by which it is carried away. The apertures 23, 24, 25 are relatively large, so that the discharge through the device is rapid and without danger of clogging. The construction of the device, and particularly the use of the tubular valve seated in a tapering recess, prevents leakage during operation.

The cap 18 preferably is formed with an internal peripheral flange or shoulder 32 adjacent the outer end of the tubular valve 17, to prevent entrance of water and the like to the annular space outside of said tubular valve in use.

It will be observed that the tubular valve 17 may be removed for repairs, such as re-grinding, without removal of the device 25 from the boiler, simply by removing the cap 18 and handle 28.

We claim as our invention—

1. A blow-off cock, comprising a casing, a tapering seat in the inner end thereof, a tubular valve rotatively mounted in said casing and spring-held to said tapering seat, entrance openings in the sides of said casing, apertures in the sides of said tubular valve adapted to register with the first apertures, a ring rotatively mounted on said casing, said casing being formed with a transverse slot covered by said ring, and a handle secured through said ring and passing loosely through said slot and screwed into said tubular valve.

2. A blow-off cock, comprising a base member adapted to be screwed into a boiler, a casing screwed on the outer end of said base member, a shell screwed in the inner end of said base member, said base member and shell being tapered to form a tapering annular seat therebetween, a tubular valve rotatively mounted in said casing and base member and tapered to fit said seat, entrance openings in the sides of said base member, openings in said shell in alinement therewith, openings in the side of said valve adapted to register with the above-mentioned openings, and means for rotating said valve.

3. A blow-off cock, comprising a base member adapted to be screwed into a boiler, a casing screwed on the outer end of said base member, a shell screwed in the inner end of said base member, said base member and shell being oppositely tapered to form a tapering annular seat therebetween, a tubular valve rotatively mounted in said casing and base member and tapered to fit said seat, said tubular valve being formed with a peripheral flange intermediate of its ends, a cap screwed on the outer end of said casing and formed with an internal shoulder, a spring coiled around the outer end portion of said tubular valve and impinging said flange and shoulder, entrance openings in the sides of said base member, openings in the shell in alinement therewith, openings in the side of said valve adapted to register with the above-mentioned openings, and means for rotating said valve.

4. A blow-off cock, comprising a casing, a shell screwed in the inner end thereof, said casing and shell being tapered to form a tapering annular seat therebetween, a tubular valve rotatively mounted in said casing and fitted to said seat, entrance openings in the sides of said casing, openings in said shell in alinement therewith, openings in the sides of said valve adapted to register with the openings of said casing and shell, a cap screwed on the outer end of said casing, a conductor leading from said cap, and means for rotating said valve.

5. A blow-off cock, comprising a casing, a shell screwed in the inner end thereof, said casing and shell being oppositely tapered to form an annular tapered seat therebetween, a tubular valve rotatively mounted in said casing and fitted to said seat, alining openings in the sides of said casing and shell, openings in said valve adapted to register therewith, said casing being formed with a transverse slot, a ring rotatively mounted on said casing and covering said slot, and a handle secured through said ring and passing loosely through said slot and secured to said tubular valve.

Signed by us at Boone, Iowa, this 14th day of January, 1915.

ROBERT L. INGERSOLL.
THOMAS J. DOUROS.
